Primary Examiner—Caron D. Veynar*Assistant Examiner*—Ricky Pham(74) *Attorney, Agent, or Firm*—Tillman Wright, PLLC; Chad D. Tillman; James D. Wright(57) **CLAIM**

The ornamental design for a cutting board assembly, as shown and described.

DESCRIPTION

FIG. 1 is a perspective view of the design for a cutting board assembly in accordance with a first embodiment of the present invention; and,

FIG. 2 is a side elevational view of the cutting board assembly of FIG. 1.

Broken lines shown in the drawings form no part of the claimed design. That which is shown in the drawings comprises that which is claimed, namely, the design shown in the perspective view of FIG. 1 and side elevational view of FIG. 2. The claimed design does not extend to the bottom; to the side opposite to the side shown in FIGS. 1 and 2; or to the end opposite to the end shown in FIG. 1.
